United States Patent Office

Des. 186,086

Patented Sept. 8, 1959

186,086

SIDING PANEL

Arthur E. Hadders, Lowell, Ind., assignor to Globe Roofing Products Co., Inc., a corporation of Indiana

Application April 26, 1956, Serial No. 41,216

Term of patent 14 years

(Cl. D68—1)

Fig. 2.

Figure 1 is a side view of a siding panel embodying my new design;

Figure 2 is an enlarged fragmentary side view taken between lines 2—2 of Figure 1;

Figure 3 is an edge view thereof; and

Figure 4 is an enlarged fragmentary sectional view thereof as seen in the direction of line 4—4 of Figure 1.

I claim:

The ornamental design for a siding panel, as shown.
